UNITED STATES PATENT OFFICE.

FRANK BOWLEY MITCHELL, OF HOVE, ENGLAND.

SELF-STOPPING AND SELF-REPEATING MECHANISM FOR CRAMOPHONES, TALKING MACHINES, AND THE LIKE.

Application filed May 15, 1925, Serial No. 30,628, and in Great Britain May 14, 1924.

This invention relates to a type of stop or repeat apparatus for gramophones, talking machines and the like operated by irregularities of the surface of the record disc itself. According to my invention I have a governing member for operating brake or repetition mechanism, arranged to be carried across the record during "playing" so that its operation shall be prevented by 10 the record groove and permitted to operate when it reaches the end of the groove. Thus, on or near the reproducer or sound box I place a member carrying one or more tracers fine or thin enough to enter the record 15 groove (hereinafter called the tracer) which may be made of metal too soft to wear the record or provided with a sapphire point or the like, and the tracer is so shaped or mounted that it shall transmit as little sound 20 as possible.

I also have a special arrangement of cam action for operating the repetition at the outer edge.

The tracer is so mounted that when the 25 stylus is finishing its work on the record the tracer point shall be in the last circle of the record groove.

The tracer is mounted on a rocking bearing so that its point shall have movement 30 towards the finish of the radial path of the stylus over the record.

The movement of the tracer on its bearing when it can slip on the smooth part of the record releases operating mechanism for the 35 purpose of brake or repetition.

The tracer point may be a little in advance of its line of pivotuation inwards towards the record axis so that its vertical pressure on the record, when in action, will 40 give a spring pressure inwards and will cause it to turn inwards on its bearing as soon as it can slip.

If the tracer is working in a groove which is in advance of the groove in which the 45 stylus is working, then the lateral movement of the reproducer in the ordinary manner will help to force the tracer out of the last groove by its contact with a part, on to the smooth part, should the groove not have a 50 natural run out from the end.

This tracer pushing part may also form a leg so that in the event of the reproducer falling on the record or turntable when it has no stylus needle in it, the shock will be

received by the leg and the parts will not be 55 broken. In practice it is found that the tracer may be made of tempered steel wire like ordinary sewing needles but bent to a certain shape shown in the accompanying drawings to prevent sound transmission. 60

The invention also comprises sundry apparatus for repetition purposes; that shown in the accompanying drawings being in the form of a double resetting cam operated by contact with the record. 65

To avoid complication I have only shown one form of the invention but many forms have been made by me during experiments and of course the invention is capable of 70 many modifications.

I will now proceed to describe the invention in detail, the novel features of which I will finally point out in the appended claims, reference being had to the accompanying drawings wherein:— 75

Fig. 1 is a perspective front elevation of a reproducer or sound box fitted for brake action only, on the surface of the record, mounted on an ordinary tone-arm which shows a stop arrangement to prevent the reproducer passing off the record, with the stylus S in action in the record groove. 80

Fig. 2 is the same, with the stylus lifted by the brake B, which is in action on the record R. 85

Fig. 3 a left-face or end view of the stylus part of the reproducer with the stylus S in action and just reaching the end of the record groove R¹. It also shows the tracer A about to leave the record or be pushed out, and the dotted part shows the tracer A pushed out or after it has slipped on the smooth part of the record. 90

Fig. 4 is a perspective view of a tracer A and its rocking pivotuation A¹. From this can be seen the means by which—when it rocks—the arm A² allows the brake friction pad B¹ to fall into action to allow the drag of the moving record to lift the reproducer and stylus out of action as shown in Fig. 100 ure 2.

Fig. 5 shows the same apparatus with the addition of the double-resetting cam C, C¹.

Fig. 6 shows a cam and brake or friction member with the cam slightly turned so that the stop rides on the moving record preventing contact of the moving cam with the record until the member can pass over the 105

outer edge of the record as shown in Figure 7 and the reproducer is in position for restart.

Fig. 7 in this the cam has turned further until the cam has made contact by presenting a longer radius; now the moving record will get a grip of same and complete the resetting by turning the cam round and lifting the friction member.

Fig. 8 shows how it resets the brake member B and lowers the stylus by presenting a receding face to the record as it turns.

Fig. 9 is a plan of a rocking member showing a hole A³ and groove A⁴ to receive the end of the tracer A⁵—the clamp A⁶ is shown turned out of action.

Fig. 10 is a tracer wire.

Fig. 11 shows the two Figures 9 and 10 clamped together.

Figure 1 shows an ordinary gramophone turntable with a record disc R to turn in the direction of the arrow. The tracer A is in action thereon. The tone arm is mounted to rotate in the fixed bearing M. The reproducer may be turned upon axis T³ out of action, with the stylus pointing upwards, when not in use. Brake action only is shown.

The action is as follows;—A needle S is inserted and the machine set in motion, the tracer A enters a record groove inwards of that of the stylus, as the machine works the whole is gradually approaching the centre of the record, the tracer will reach the last circle of the record groove before the stylus and will either jump out towards the record centre of itself or will wait to be pushed out by the continued inward travel of the stylus and reproducer.

When the tracer and its holder A³ moves with the extension A² the movement of the latter allows the lever B to fall and the part B¹ touching the moving record, the latter pulls the lever to the vertical position. As lever B is too long, this raises the reproducer out of action as shown in Figure 2 and the rub of the friction pad B¹ on the record causes the brake pad B¹ to be moved outwards by the frictional tangential drag on the record and after two or three revolutions of the record the machine will stop. The pull of the moving record on the pad will move the arm outwards towards X and to prevent the reproducer passing over the edge of the record a stop L is provided with which the member T² is adapted to engage.

The stop is adjustable for different size records as shown by the steps L¹ and L².

A spring may be provided to cause the arm to go outwards as soon as the stylus and reproducer are lifted as stated.

I will now more fully describe the action with reference to Figures 3, 4, 9, 10 and 11. The tracer pin is in this form, a thin needle with the working point bent at nearly a

right angle, it is mounted in the groove A⁴ of the block A⁸, the end A⁷ entering the small hole A³ Figure 9 then the clamp A⁶ is turned to cover same and the screw is tightened as shown in Figure 11.

This tracer is mounted on the reproducer T¹ so that its point projects lower than the point of the stylus when the latter is lifted and will touch the record before the stylus when placing the reproducer in position—thus it always works under spring pressure on the record.

It will be noticed that the tracer point is not directly under the line of its pivot when at work, see Figures 11 and 3, so that the spring pressure on its point will, while turning the block on its pivot, cause the point of the tracer to move to the left, in other words the spring pressure of the tracer on the record gives the point a spring tendency to jump sideways. It cannot however travel sideways and the block cannot turn while the point is unable to slip as shown in Figure 3 in a record groove, but as soon as the point gets on a smooth part of the record as in Figure 2 and by dotted lines in Figure 3 upward pressure on the tracer point (its spring pressure) causes it to jump inwards as shown moving the block A⁸ and the extension A² which latter permits the brake or operating member B to fall and either stop the machine or repeat.

Referring to Figures 5, 6, 7 and 8 the reproducer lifting parts are here shown as previously described but with the addition of repetition parts which act as follows:—Cam wheel C is mounted on an axis C⁶ and may be surrounded by a rubber band as it is to rotate by friction on the record.

When the parts mentioned come into action at the finish of the record and the brake member B falls the pin B⁷ can pass in and move with member B from the position shown in Figure 5 to the position shown in Figure 6.

The cam wheel is heavy on the right hand so that if free it will turn. In the position Figure 5 this wheel cannot turn as the stop block C³ on the cam C cannot pass the pin B⁷ in B, but directly the member B falls, pin B⁷ no longer prevents rotation of cam C Figure 6. In this position the tone arm T is being moved out and the reproducer is lifted by the friction member B. As the arm C¹ rides on the record surface the cam C cannot turn enough to touch the record until it reaches the edge and the arm C¹ passes over the edge of the record (the cam remaining over the record). Now the cam C can turn and arm C¹ falls still more as shown in Figure 7—the cam now making contact with the record. The turning record now grips same and causes it to turn completely. Directly the record begins to turn the cam wheel the reproducer is still

further lifted and the rotation of the cam wheel resets the lever B by means of the small cam C² pushing the pin B', this is done very quickly and the stop C³ meets the 5 pin B' which stops its further rotation as shown in Figure 5, and the small recess C⁴ shown in Figure 7 blocks the return (rebound) passage of the pin B' and lever B to the left otherwise there is danger of its

10 rebounding inwards at each operation and not coming to rest. This stop is long enough for the tracer member A to return to the position shown in Figure 4 by gravity where it holds up the member B.

15 To be quite sure that the reproducer when it is thrown outwards for restart stops exactly at the correct position I provide a stop member having stop positions adjustable for brake purposes, for ten inch records or for 20 twelve inch for example shown at L Figure 1. This stop member may have an adjustable screw in each face for fine adjustment at L¹ and L² or the arm bearing may be arranged to slide laterally.

25 There is a part at T³³ Figures 3 and 5 which serves two purposes: One is that if a reproducer is allowed to fall on a record when there is no stylus needle in, the shock will be received by the part and no harm 30 done to the working parts. The other purpose is that if there is any difficulty (owing to an extra deep groove) for the tracer point to go out of the last groove the continued movement of the approaching reproducer 35 will force it out by means of the extension T³³.

I claim:—

1. Mechanical automatic control mechanism for talking machines and the like, comprising a tone arm control device for co-acting with the record, and a tracer to actuate the device and tracking in the record groove in advance of the talking machine stylus.

45 2. Automatic mechanism for talking machines, comprising a tone arm control device for coacting with the record, a tracer tracking in the record groove in advance of the talking machine stylus, and means operated by the tracer for applying the control device to the record at the end of the reproduction upon the escape of the said tracer from the inner end of the record groove.

55 3. Automatic mechanism for talking machines and the like, comprising a tone arm control device for coacting with the record, a resilient tracer carried with the talking machine reproducer and tracking in the record groove and movable therefrom at the end 60 of the reproduction, and a release device operated by the movement of the tracer for permitting the control device to be operated.

45 4. Automatic mechanism for talking machines and the like, including a tone arm control device for coacting with the record,

means for preventing the operation of the control device during reproduction, a tracer tracking in the record groove in advance of the talking machine stylus, and means operated by the tracer for releasing said control device preventing means at the end of the reproduction and upon the escape of the said tracer from the inner end of the record groove.

5. Automatic repeating mechanism for talking machines and the like comprising a brake pad, means normally preventing the operation of the brake pad during reproduction, a tracer engaging the record groove to release said brake pad restraining means at the end of a reproduction so that the brake pad contacts with the record to move the reproducer to the outer part of the record and means for automatically re-setting the brake pad and its restraining means.

6. Automatic repeating mechanism for talking machines and the like comprising a brake pad, means normally preventing the operation of the brake pad during reproduction, a tracer engaging the record groove to release said brake pad restraining means at the end of a reproduction so that the brake pad contacts with the record to move the reproducer to the outer part of the record, and a weighted cam adapted to co-operate with the record for re-setting the brake pad and its restraining means.

7. Automatic repeating mechanism for talking machines and the like comprising a brake pad, means normally preventing the operation of the brake pad during reproduction, a tracer engaging the record groove to release said brake pad restraining means at the end of a reproduction so that the brake pad contacts with the record to move the reproducer to the outer part of the record, a weighted cam adapted to co-operate with the record for re-setting the brake pad and its restraining means, and means for preventing said weighted cam from contacting with the record until the reproducer reaches the outer edge of said record.

8. Automatic repeating mechanism for talking machines and the like comprising a brake pad, means normally preventing the operation of the brake pad during reproduction, a tracer engaging the record groove to release said brake pad restraining means at the end of a reproduction so that the brake contacts with the record to move the reproducer to the outer part of the record, a weighted cam adapted to co-operate with the record for re-setting the brake pad and its restraining means, and an arm movable with said cam and adapted to ride upon the record surface so as to prevent the cam contacting with the record until the reproducer has reached the outer edge thereof.

9. Automatic repeating mechanism for talking machines and the like comprising a

4
brake pad, means normally preventing the operation of the brake pad during reproduction, a tracer engaging the record groove to release brake pad restraining means at the 5 end of a reproduction so that the brake contacts with the record to move the reproducer to the outer part of the record, a weighted cam adapted to co-operate with the record for re-setting the brake pad and its restraining means and a stop device for preventing the reproducer moving beyond the outer edge of said record.

10. In a talking machine or the like, a tracer tracking in the record groove, a tone 15 arm control device for coacting with the record and actuated by the tracer upon its escape from said groove.

11. In a talking machine and the like, a resilient tracer tracking in the record groove, a reproducer supporting the tracer and acting to force the tracer out of the record groove at the end of the reproduction, and a control device for the reproducer actuated by said tracer at the end of a reproduction. 20

12. In a talking machine and the like, the combination of a reproducer including a stylus and a tracer tracking in the record groove in advance of the stylus, and a reproducer control device coacting with the record and actuated by the said tracer at the 25 end of the reproduction. 30

Dated this 1st day of May 1925.

FRANK BOWLEY MITCHELL.
